PROCESSES OF TREATING HYDROCARBONS

Harold V. Atwell, White Plains, N. Y., assignor to
 Gasoline Products Company, Inc., Newark,
 N. J., a corporation of Delaware

Application January 23, 1934, Serial No. 707,867
 Renewed January 25, 1936

19 Claims. (Cl. 196—48)

This invention relates to processes for converting relatively heavy higher boiling hydrocarbon oils into lighter lower boiling hydrocarbon oils such as motor fuel, and pertains more particularly to processes for the production of relatively high anti-knock motor fuel from heavier oils, wherein provision is made for reacting any fixed gases or other hydrocarbons lighter than desired in gasoline, with heavier products to form final desired distillate.

It is an object of my invention to provide an improved process whereby relatively heavy oil is first subjected to a cracking operation wherein lighter products in the desired boiling range, for example in the gasoline boiling range, are produced, as well as heavier products and also mainly gaseous hydrocarbons, which are of such low boiling point as to be undesirable in the final product; and wherein these mainly gaseous hydrocarbons are mixed with products too heavy for inclusion in the final desired product, and subjected to heat treatment, whereby additional quantities of final desired products are formed, as well as hydrocarbons heavier than desired in the final product and suitable for cracking to make high anti-knock gasoline or other desired relatively light hydrocarbons.

In accordance with my invention the products of any cracking operation, preferably a high crack per pass cracking operation or a reforming operation, are fractionated in the conventional manner to yield a desired distillate and a potential cycle stock in the gas oil boiling range. This cycle stock oil is passed to a separate reverting zone such as heating coil, with or without a soaking drum, wherein it is contacted with gas containing olefins, such as uncondensed gas from the main cracking operation, under conditions favoring a reaction between the gas and the oil. Preferably high pressure such as 1000 pounds per square inch or more, and a moderate temperature such as 800° to 950° F., will be used in this stage, although lower pressures may be used if desired. Under these conditions the naphthenic, and to some extent the olefinic liquids, will react with the olefinic gas to make additional liquid hydrocarbons. At the same time the paraffinic constituents of the charging stock will be cracked to lighter products, e. g. those in the gasoline boiling range. In the separating zone handling the effluent from the reverting zone or heating coil, which treats the cycle stock and gas, the light products from the cracking of paraffinic components are passed overhead and subjected to fractionation. Heavy reversion products resulting from the re-

action of olefinic gas with the non-paraffinic components of the charging stock are removed from a lower point in the fractionating zone and cracked in a separate operation. Further cracking is preferably accomplished in a separate coil, although optionally in the same furnace with the other coil, so that optimum cracking conditions may be applied to these reversion products.

Optionally the reversion products may be recycled to the main cracking operation. A product of this cracking of reversion products will be a high anti-knock gasoline which can be blended with the distillate from the main cracking coil. The products from the intermediate or reversion stage may be subjected to additional fractionation for the separation of the heaviest fraction, in case it is found difficult to limit the reaction so that the total product is crackable as a clean stock. In this case, a relatively light gas oil cut, heavier than that desired for the final product, may be separately removed and recycled to the initial cracking zone, while heavier reaction products may be passed through a separate cracking zone.

The above mentioned and further objects and advantages of my invention, and the manner of attaining them, will be made clear in the following description taken in conjunction with the accompanying drawing.

In the drawing the single figure illustrates diagrammatically an apparatus for carrying out the process of my invention.

Referring more particularly to the drawing, reference numeral 1 indicates a charging line from which fresh charging stock, such, for example, as clean gas oil, is forced by pump 2 through the coils of cracking furnace 3, wherein it is subjected to a conventional cracking operation. This cracking operation is preferably carried out in the vapor phase at relatively high cracking temperature, whereby relatively high anti-knock gasoline is formed, the cracking temperature preferably being above 900° F., for example, about 1000° F. The pressure is preferably relatively low, for example from 100 to 400 pounds per square inch, most desirably 195 to 225 pounds per square inch. From the cracking furnace 3 the cracked products pass through pipe 4 into reaction chamber 5 wherein further conversion thereof takes place in the usual manner. The cracking to products in the gasoline boiling range, per pass, may be in the neighborhood of 15% to 25% or more. When a very clean charging stock is used the cracking per pass may be raised to as high as 40% or 50%, or more, by providing high

temperatures and pressures and short times of contact. The resulting soaked or digested products travel through pipe 6 into evaporator 7 wherein vapors separate from liquid residue in the well known manner, the residue being drawn off through line 8 and the vapors passing overhead through line 9 into fractionator 10. In the fractionator 10 the vapors are subjected to fractional condensation in the usual well known manner, the fractionated vapors of desired boiling characteristics passing off from the top of the fractionator through pipe 11 into condenser 12 from which the resulting condensate passes to the receiving drum 13. This drum is provided with a draw-off pipe 14 for removing the finished products, e. g., gasoline and with a gas draw-off line 15 having compressor 20 which forces the gas into a pipe 17, in mixture with reflux condensate withdrawn from the bottom of the fractionator 10 through pipe 16.

Additional gas of a similar nature or richer in olefins or reactive oil, or both, may be introduced from an external source through the valved line 71, if desired, in order to establish balanced conditions of operation. Alternatively part of the gas may be diverted from the process through line 72, or the gas may be freed from undesired constituents, e. g. hydrogen and methane, by being passed through a separating apparatus, shown diagrammatically at 13, the undesired constituents being diverted from the process through valved line 74 while the rest are returned to the line 15. Reference numerals 15 and 76 indicate pipes for conducting the gas to and from the separating apparatus and numerals 71, 78 and 79 refer to control valves.

The reflux condensate is forced by pump 19 in mixture with the gas from line 15 through the coils of reverting furnace 18. In this reverting furnace the mixture is preferably raised to a temperature in the neighborhood of 900° F. under a pressure which may vary considerably, but which is preferably in the neighborhood of 1000 pounds per square inch or more. The temperature may range suitably from 850° to 900° F., for example, while the pressure may extend from 200 pounds per square inch upward. The exact conditions of temperature and pressure selected for the reversion operation would depend upon the character of the reflux condensate and of the gas supplied to the reverting zone as well as the respective quantities thereof. In general it may be said that the richer the gas is in olefins, the lower the temperature and pressure that may be used in the reverting zone. High concentration of naphthenes in the reflux condensate favors the reaction and so where the concentration of such naphthenes is relatively high the temperature and pressure in the reverting zone may be reduced. Increased pressure in the reverting zone favors the reaction and therefore an increase in pressure tends to produce better results, other factors being equal. The products from the furnace 18 pass through pipe 21 into reaction chamber 22 where in additional conversion takes place, the digested products travelling through conduit 24 into the evaporator 25, wherein vapors separate from liquid residue, the latter passing off from the evaporator through draw-off line 26 while the vapors move upwardly through the evaporator, being partially fractionated if desired by action of cooling coil 27, which may be supplied with cooling fluid from any suitable source, the vapors remaining uncondensed passing off from the top

of the evaporator, through vapor line 28 into fractionator 29.

In this fractionator the vapors undergo fractionation in the usual well known manner, cooling for causing the necessary refluxing action being supplied by means of cooling coil 30, or in any other suitable manner. The vapors remaining uncondensed at the top of the fractionator and having the desired boiling characteristics, pass off through vapor line 31 and condenser 32, resulting condensate being collected in the receiving drum 33. This drum has the usual gas draw-off line 34 and distillate draw-off line 35, through which the distillate may be withdrawn from the process separately if desired. As a result of the fractionating taking place in the fractionator 29 a relatively heavy reflux condensate is collected in the base of the fractionator which is passed preferably through line 36 to the cracking furnace 39 by action of pump 38, although any desired portion of this heavier reflux condensate may be withdrawn from the process through line 80. The heavy condensate so collected would consist largely of products of the gas reversion operation having a relatively low hydrogen to carbon ratio, this condensate being especially adapted for the production of high anti-knock gasoline.

As a result of the reaction taking place in the reverting zone a portion of the paraffinic hydrocarbons supplied may pass through substantially unchanged and should be separated by fractionation and returned to the initial cracking zone. This may be accomplished by placing in the fractionator 29 an intermediate trap-out tray 81 which serves to collect a relatively light reflux condensate, e. g. of a light gas oil nature, which may be returned through line 82, by action of pump 83, to the cracking furnace 3 for further cracking.

In case all of the reflux condensate is withdrawn from tray 81 through line 82, cooling may be supplied below the trap-out tray in any well known manner as by directly introducing a cooling oil.

The cracking furnace 39 is preferably operated so as to heat the oil passing therethrough to a moderately high cracking temperature, of, for example, from 850° to 950° F., under a moderate pressure of, for example, 200 pounds per square inch to 400 pounds per square inch. The resulting cracked products pass through line 40 to the evaporator 7 along with the cracked products from the reaction chamber 5, the valve 84 being open and the valve 85 being closed.

If desired, a separate evaporator 49 may be furnished for separating the cracked products from 39 into vapors and liquids, the separated vapors passing to fractionator 10.

The pressure in the evaporator 7 need not be limited strictly to some fixed value, but is more suitably about 200 pounds per square inch. Higher or lower pressure may be used in accordance with usual cracking practice.

Valve 41 is inserted in the line 6 to provide for any desired pressure differential between the reaction chamber and the evaporator. Valve 42 provides any necessary control for regulating the amount of reflux condensate passed from the fractionator 10 to the reverting furnace 18. Any desired portion of this reflux condensate may be diverted from the process through the valved line 43, in order to secure balanced operating conditions. Draw-off line 44 is furnished at the base of reaction chamber 5 so that any liquid

which may collect from time to time may be drawn off. Ordinarily where soaking is accomplished in the vapor phase this draw-off line would not be used. Valves 45, 46 and 47 are 5 interposed in their respective pipes so that the reaction chamber 22 may be cut out of operation if desired, thereby permitting the products from furnace 18 to pass directly through line 24 into the evaporator tower 25. The pressure in the 10 evaporator 25 may be regulated with respect to that in the reverting furnace 18 by means of valve 48. The pressure in the evaporator tower is preferably about 200 pounds per square inch.

The cooling supplied to the evaporator 25 by 15 action of cooling coil 27 is preferably so regulated that the vapors passing overhead have boiling characteristics corresponding to an end point of from 700° to 800° F. The reflux condensate removed from the base of fractionator 29 would 20 therefore have an end point of from 700° to 800° F., approximately, while the end point of any condensate removed from the trap-out tray 81 would be less, for example 500° to 700° F. Any 25 products too heavy for further cracking in the furnace 39 may be prevented from entering the fractionator 29 by increasing the refluxing action caused by the cooling coil 27.

The preceding operation is normally carried out with valve 85 closed and valve 84 open, but, 30 when desired, valve 84 may be closed and valve 85 opened thereby causing the cracked products from cracking furnace 39 to pass through pipe 471 and control valve 481 into evaporator 49 wherein vapors separate from liquid residue. 35 The liquid residues may be withdrawn separately through line 50 and the vapors may be passed overhead through vapor line 51 into the fractionator 10. This arrangement permits the tars from evaporator 7 and evaporator 49 to be 40 separately eliminated, an advantage since the tars may have different characteristics. This operation is permitted when valve 52 is closed, and valve 53 opened, but if desired the valve 53 may be closed and valve 52 opened, thereby passing the vapors from the evaporator 49 through line 45 54 into the fractionator 55, wherein they are subjected to fractionation separately from the products in fractionator 10. This fractionation is carried out in the usual well known manner 50 with the fractionated vapors passing off through vapor line 56 and condenser 57, the resulting condensate being collected in receiving drum 58. The distillate from receiving drum 58, e. g., gasoline, 55 may be separately diverted from the process through valved line 59, or may be blended with the distillate collected in receiver 13, by utilization of cross-over line 60, and proper manipulation of valves 61, 62 and 63. The reflux condensate from fractionator 55 is preferably returned 60 through valved pipe 64, by action of pump 65, into line 17 leading to the reverting furnace 18, in any desired quantity, any excess of reflux condensate being diverted from the process through 65 valved pipe 66. The tars withdrawn from the evaporator 7, evaporator 25 and evaporator 49 may be withdrawn from the process separately or in any desired admixture either for use as a 70 commercial product, for flashing or any other well known treatment. Distillate collected in receiver 33 may be blended with distillates from receivers 13 and 58, or either of them, as desired, by way of conduit 86. Gases from receiver 58 may be passed through line 67, by action of pump 75 68, into line 17, for further reversion, or alter-

natively be first freed of undesired constituents in the apparatus 73, being delivered thereto by pipe 87. Or any part or all of the gas may be diverted from the process by way of pipe 69.

Operation

In carrying out the process, fresh charging stock, for example a clean gas oil of about 35° A. P. I. gravity, is introduced through the charging line 1 and passed through the cracking furnace 3 and reaction chamber 4, wherein the oil is subjected to a cracking operation of any well known type, but preferably a vapor phase cracking operation. The conditions of cracking to which this oil is subjected are not critical but 15 may vary considerably in accordance with well known practice. By way of illustration it may be said that the cracking can be successfully carried out at temperatures of from 900° to 1100° F., most desirably about 1000° F. The pressure 20 is also not critical but is suitably in the range of 100 to 400 pounds per square inch, most desirably about 200 pounds per square inch. The resulting cracked products are passed through line 6 into evaporator 7 and therein separate into 25 vapors and liquid residue in the well known manner. This evaporator is preferably operated at substantially the same pressure as that of the cracking furnace 3, e. g., 200 pounds per square inch, although it may be operated at considerably lower pressure than that of the cracking furnace if desired. The vapors pass overhead from the evaporator through line 9 into the fractionator 10 and are there subjected to fractionation in the usual well known manner. The fractionated vapors, which have the desired boiling characteristics, pass overhead through line 11 and condenser 12, the condensate being collected in the receiver 13 in the form of a desired product, for example, gasoline.

In this receiver gas separates from the distillate and passes overhead through line 15 and is forced by action of compressor 20 into the line 17, in combination with any desired quantity of reflux condensate withdrawn from the fractionator 10, and, if desired, additional gas or oil from an external source by way of line 71, the combination of condensate and gas passing through the coils of reverting furnace 18. Ordinarily all of the reflux condensate from the fractionator 10 will be passed to the reverting furnace, but if desired a portion may be diverted through line 43. Likewise part of the gas from receiver 13 may be diverted from the process 55 through pipe 72.

In the reverting furnace the introduced products are subjected to such conditions of temperature and pressure as favor a reaction between the gas and the oil. Preferably high pressures such as 1000 pounds per square inch and moderate temperatures such as 800° to 950° F. will be used in this stage. Under these conditions the naphthenic and the olefinic liquids will react with the olefinic constituents of the gas to make relatively heavy oil. At the same time the paraffinic constituents of the charging stock will be cracked to lighter products, largely in the gasoline boiling range. Preferred conditions for carrying out the operation in the reverting furnace are a temperature of about 900° F. and a pressure in the neighborhood of 1000 pounds per square inch or more. However, a lower pressure may be used if desired, any value between 200 and 1000 pounds per square inch proving effective. The richer the 75

content of olefins in the gas from the receiving drum 13 and the higher the concentration of naphthenes in the liquid condensate withdrawn from the fractionator 10, the more active the reaction taking place in the reversion furnace and reaction chamber. With this fact in view adjustments of the conditions in the furnace may be made, the higher the content of olefins and/or naphthenes in the gas and liquid oil, respectively, the lower may be the pressure in the cracking zone and also the lower the temperature used for creating the reaction. The cracked and polymerized products are subjected to further reaction in the chamber 22, if that reaction chamber be used, and the resulting reacted products are introduced through line 24 and control valve 48 into the evaporator 25, which is preferably operated under a pressure substantially the same as that of the evaporator 7. However this pressure may be higher than that of the evaporator 7, if desired, the necessary adjustments being obtained by means of valve 48.

In the evaporator 25 vapors separate from liquid residue, the latter being drawn off through line 26 while the former travel upwardly through the vessel, any necessary cooling being effected by aid of cooling coils 27 or in any other suitable manner.

The uncondensed vapors pass off from the evaporator 25 through vapor line 28, into fractionator 29, wherein they undergo fractionation in the usual manner, any necessary refluxing action being supplied by means of cooling coil 30 or in any other well-known manner. The cooling of the top of the evaporator 25 by cooling coil 27 is preferably so regulated that the vapors passing to the fractionator 29 have a boiling characteristic corresponding to an endpoint of from 700° to 800° F., being in the nature of a heavy gas oil. The reflux condensate collected in the base of the fractionator therefore also has an endpoint of about 700° to 800° F., while an intermediate condensate in the nature of a light gas oil, is collected on the trap-out tray 81 and may have an end point of about 500° to 700° F. This light gas oil is preferably recycled to the cracking furnace 3, being mainly paraffinic in nature. The heavy gas oil collected in the base of the fractionator will have been formed mainly by the reaction of gas with heavier products in the reverting furnace 18 and will have a relatively low ratio of hydrogen to carbon. This heavy gas oil, which is suitable for cracking for the production of relatively high anti-knock gasoline, is removed from the base of the fractionator 29 and passed in any desired quantities through the line 36 into the coils of cracking furnace 39, wherein it is raised to a cracking temperature of a moderate value, for example, 850° to 950° F., under a pressure preferably in the range of from 200 pounds to 400 pounds per square inch. Any desired part of the heavy condensate from the base of fractionator 29 may be diverted through pipe 80 to establish balanced condition. The cracked products pass from the cracking furnace 39, preferably through line 40 into the evaporator 7, valve 84 being open and valve 85 being closed.

In the evaporator 7 the cracked products are subjected to the same treatment as that received by the products from reaction chamber 5, as already described.

The fractionated vapors, having the desired boiling characteristics, pass off from the top of fractionator 29 through vapor line 31 and con-

denser 32, the resulting condensate being collected in receiver 33. This condensate has the desired boiling characteristics and may be, for example, gasoline. Line 35 is provided so that the liquid may be diverted from the process, or alternatively may be blended with distillate from the receivers 13 and 58, or either of them, by way of lines 86 and 60. Gases may be removed from the receiver 33 by way of pipe 34.

According to a different mode of operation, valve 84 may be closed and valve 85 opened, thereby transferring the cracked products through line 41 into the evaporator 49, wherein vapors separate from liquids in the usual manner, the liquids being drawn off through line 50, either for use as fuel oil, or for flashing or any other well known treatment, while the vapors pass through line 51 into the fractionator 10 for fractionation therein. In this method of operation, valve 53 is open and valve 52 closed.

If desired the valve 53 may be closed and valve 52 opened, thereby diverting the vapors from evaporator 49 into the fractionator 55, wherein they are fractionated separately from the products in the fractionator 10. This method of operation has the advantage that it permits the individual control of the treatment of cycle stock from the fractionator 5.

Ordinarily all of the reflux condensate from fractionator 55 will be returned by pump 65 through line 64 into line 17, for treatment in the reverting furnace 18, but if desired a portion of this reflux condensate, or all of it, may be diverted from the process through line 66. The vapors pass overhead through line 56 and condenser 57, resulting condensate being collected in receiving drum 58 as a desired product, e. g. gasoline. This gasoline may be drawn off separately through line 59 or blended with the gasoline distillate collected in either of receiving drums 13 and 33, or both of them, by agency of line 60, the necessary control of flow being effected by the several valves provided, in an obvious manner.

The gas separated from the liquid in receiving drum 58 may be returned directly to the reverting furnace 18 by way of pipe 67, under pressure generated by compressor 68, or may be first freed of undesired constituents, in apparatus 73. If desired part of this gas, or all of it, may be diverted from the process through valved line 69. The products of the separate cracking of the heavy gas oil in the cracking furnace 39 will be a high anti-knock gasoline which is suitable for blending with the distillate from the main cracking furnace 3 or from reverting furnace 18 or for any other blending purpose desired. A reaction chamber may be used with the furnace 39, if desired.

This operation is especially suitable for use in connection with a reforming process, also, since it provides steps for converting the fixed gases formed to a desired liquid oil. In case reformation is to be carried out as a primary step, the cracking furnace 3 and reaction chamber 5 would be operated in such manner as to effect the desired reforming reaction or formation of higher anti-knock products. In this case the charging stock would be gasoline of low-anti-knock characteristics. Reforming processes causes the generation of a relatively large amount of gas and this gas may be converted to products in the boiling range of the final desired product, by treatment in the manner described hereinbefore.

The process described hereinbefore enables the

5 avoidance of excessive amounts of coke which I believe result from the reaction of relatively light olefinic materials, such as ethylene and propylene, with naphthenic and possibly unsaturated liquids, somewhere in the heavy naphtha, kerosene or gas oil boiling range, which occurs in an ordinary cracking operation where recycling is employed. By preventing recycling or the return of such reflux condensate to the cracking operation, I am able to prevent the undesired reaction 10 of gas and liquid mentioned above, and am able to produce interaction of these products in a separate zone, so as to form additional charging stock for a subsequent cracking operation, as well 15 as additional light products in the desired boiling range.

By gas reversion is meant the reaction between normally gaseous hydrocarbons, particularly gaseous olefins, and the relatively heavy liquid products of cracking such as cracked tar, cracked gas oil or the like. The exact nature of the reactions is unknown but it is probable that the addition of olefinic side chains to naphthenic and aromatic compounds proceeds extensively. Because of the variety and complexity of the ring compounds in cracked oils it is obviously impossible to describe these reactions in detail. It is probable that decomposition and recombination proceed simultaneously so that the gaseous hydrocarbons react in part with the active molecules or radicles resulting from the concurrent cracking of heavier hydrocarbons. A reverting zone, as the words are used in this specification, is a zone wherein the above described reversion action 35 takes place.

While I have described a particular embodiment of my invention for the purposes of illustration it should be understood that various modifications and adaptations thereof may be made within the spirit of the invention as set forth 40 in the appended claims. For example, a suitable catalyst such as aluminum chloride, or other metallic halide may be used to accelerate the reverting and/or cracking steps, being either passed through the various heating furnaces with the stock undergoing treatment, or being introduced into the several reaction chambers. In case catalysts are used lower operating temperatures are desirable.

I claim:

50 1. The process of treating hydrocarbon oil which comprises passing fresh charging stock through a cracking zone wherein it is raised to a cracking temperature and subjected to conversion, introducing the resulting cracked products into an evaporating zone wherein vapors separate from liquid residue, passing resulting vapors into a fractionating zone wherein partial condensation occurs, removing fractionated vapors from said zone, condensing the removed vapors and separately collecting resulting distillate as a desired product, removing fixed gas from said distillate, combining said gas with reflux condensate removed from said fractionating zone and passing the mixture through a reverting zone wherein it is subjected to a reverting temperature under a pressure of at least 200 pounds per square inch and reaction between the gas and liquid occurs, passing the resulting products into a separating zone 55 wherein vapors separate from liquid residue, fractionally condensing said vapors, independently of said vapors first mentioned, to separate therefrom a heavy gas oil condensate and leave undenched relatively light vapors of desired boiling characteristics, separately condensing said light

vapors and passing said heavy gas oil condensate through a second cracking zone wherein it is raised to a cracking temperature and subjected to cracking and introducing the resulting cracked products into said evaporating zone.

5 2. The process of treating hydrocarbon oil which comprises passing fresh charging stock through a cracking zone wherein it is raised to a cracking temperature and subjected to conversion, subjecting the resulting cracked products to a separating operation so as to separate vapors from liquid residue, withdrawing said liquid residue from the process and fractionating said vapors to condense products heavier than those desired in the final product, removing the fractionated vapors and condensing them to form a desired distillate, separating fixed gas from the resulting distillate in a gas separating zone and combining it with condensate formed in the fractionating operation, passing the resulting mixture 10 through a reverting zone wherein it is subjected to a cracking temperature of from 800° to 950 F. under a pressure of at least 200 pounds per square inch, separating resulting reaction products into vapors and liquid residue, withdrawing said liquid residue from the process, fractionating resulting vapors, independently of said vapors first mentioned, into vapors of desired boiling characteristics and heavy gas oil reflux condensate, 15 passing reflux condensate so formed through a separate cracking zone wherein it is raised to a cracking temperature and subjected to conversion, separating resulting cracked products into vapors and liquid residue, withdrawing said residue from the process, passing vapors so separated 20 to a fractionating operation, separate from that in which the vapors from the reversion step are fractionated, wherein fractional condensation thereof occurs, removing the fractionated vapors, condensing them and collecting the condensate 25 as a desired product and combining condensate last mentioned with distillate first mentioned to form a final desired product.

3. A process in accordance with claim 2 wherein reflux condensate formed in the last mentioned fractionating operation is returned to the reverting zone for further conversion.

4. A process in accordance with claim 2 wherein in the reverting zone the products are raised to a temperature of about 900° F. under a pressure of about 1000 pounds per square inch.

5. A process in accordance with claim 2 wherein gas formed in the last mentioned fractionating operation is returned to the reverting zone for further conversion.

6. A process in accordance with claim 2 wherein the fractionation of vapors from the two cracking operations is carried out in a single fractionating zone.

7. A process in accordance with claim 1 wherein an intermediate condensate is separated from the vapors derived from the reverting operation and is recycled to the first mentioned cracking zone for further conversion.

8. A process in accordance with claim 1 wherein said fixed gas removed from said distillate is freed of hydrogen and methane before being combined with said reflux condensate.

9. The process of treating hydrocarbon oil which comprises passing fresh charging stock through a cracking zone wherein it is raised to a cracking temperature and subjected to conversion, introducing the resulting cracked products into an evaporating zone wherein vapors separate from liquid residue, passing resulting vapors into

- 5 a fractionating zone wherein partial condensation occurs, removing fractionated vapors from said zone, condensing the removed vapors and separately collecting resulting distillate, removing fixed gas from said distillate, freeing said
10 gas of hydrogen and methane, combining the hydrogen and methane-free gas with reflux condensate removed from said fractionating zone and passing the mixture through a reverting zone
15 wherein it is subjected to reverting conditions of temperature and pressure and reaction between the gas and liquid occurs, passing the resulting products into a separating zone wherein vapors separate from liquid residue, fractionally condensing said vapors in a second fractionating zone to separate therefrom a heavy gas oil condensate and leave uncondensed relatively light vapors of desired boiling characteristics, separately condensing said light vapors and passing said heavy
20 gas oil condensate through a second cracking zone wherein it is raised to a cracking temperature and subjected to cracking and introducing the resulting cracked products into said evaporating zone.
- 25 10. The process of treating hydrocarbon oil which comprises passing fresh charging stock through a cracking zone wherein it is raised to a cracking temperature and subjected to conversion, introducing the resulting cracked products into an evaporating zone wherein vapors separate from liquid residue, passing resulting vapors into a fractionating zone wherein partial condensation occurs, removing fractionated vapors from said zone, condensing the removed vapors and separately collecting resulting distillate, removing fixed gas from said distillate, freeing said gas of hydrogen and methane, combining the hydrogen and methane-free gas with reflux condensate removed from said fractionating zone and passing
30 the mixture through a reverting zone wherein it is subjected to temperatures of from 800° to 950° F., under a pressure of from 200 to 1000 pounds per square inch, and reaction between the gas and liquid occurs, passing the resulting products into a separating zone wherein vapors separate from liquid residue, fractionally condensing said vapors to separate therefrom a heavy gas oil condensate and leave uncondensed relatively light vapors of desired boiling characteristics, separately condensing said light vapors and passing said heavy gas oil condensate through
35 a second fractionating zone to separate therefrom a heavy gas oil condensate and leave uncondensed relatively light vapors of desired boiling characteristics, separately condensing said light vapors and passing said heavy gas oil condensate through a second cracking zone wherein it is raised to a cracking temperature and subjected to cracking, introducing the resulting cracked products into said evaporating zone, separating fixed gas from said light vapors last-mentioned and combining fixed gas so separated with the said mixture of gas and reflux condensate for passage through
40 said reverting zone.
- 45 11. The process of treating hydrocarbon oil which comprises passing fresh charging stock through a cracking zone wherein it is raised to a cracking temperature and subjected to conversion, introducing the resulting cracked products into an evaporating zone wherein vapors separate from liquid residue, passing resulting vapors into a fractionating zone wherein partial condensation occurs, removing fractionated vapors from said zone, condensing the removed vapors and separately collecting resulting distillate, removing fixed gas from said distillate, freeing said
50 gas of hydrogen and methane, combining the hydrogen and methane-free gas with reflux condensate removed from said fractionating zone and passing the mixture through a reverting zone wherein it is subjected to reverting conditions of temperature and pressure and reaction between the gas and liquid occurs, passing the resulting products of reaction into a separating zone wherein vapors separate from liquid residue, fractionally condensing said vapors in a second fractionating zone to separate therefrom a heavy gas oil condensate, separately condensing the resulting fractionated vapors, passing said heavy gas oil condensate through a second cracking zone wherein it is raised to a cracking temperature and subjected to conversion, introducing the resulting cracked products into a second evaporating zone wherein vapors separate from liquid residue,
- 55 12. The process of treating hydrocarbon oil which comprises passing fresh charging stock through a cracking zone in the absence of added fixed gas, wherein it is raised to a cracking temperature and subjected to conversion, introducing the resulting cracked products into an evaporating zone wherein vapors separate from liquid residue, passing resulting vapors into a fractionating zone wherein partial condensation occurs, removing fractionated vapors from said zone, condensing the removed vapors and separately collecting resulting distillate, removing fixed gas from said distillate, freeing said gas of hydrogen and methane, combining the hydrogen and methane-free gas with reflux condensate removed from said fractionating zone and passing the mixture through a reverting zone wherein it is subjected to reverting conditions of temperature and pressure and reaction between the gas and liquid occurs, passing the resulting products into a separating zone wherein vapors separate from liquid residue, fractionally condensing said vapors in a second fractionating zone to separate therefrom a heavy gas oil condensate and leave uncondensed relatively light vapors of desired boiling characteristics, separately condensing said light vapors and passing said heavy gas oil condensate through a second cracking zone wherein it is raised to a cracking temperature and subjected to cracking, introducing the resulting cracked products into said evaporating zone, separating fixed gas from said light vapors last-mentioned and combining fixed gas so separated with the said mixture of gas and reflux condensate for passage through
60 said reverting zone.
- 65 13. The process of treating hydrocarbon oil which comprises passing fresh relatively heavy charging stock through a cracking zone wherein it is raised to a cracking temperature and subjected to conversion, introducing the resulting vapors into a fractionating zone wherein partial condensation occurs, removing fractionated vapors from said zone, condensing the removed vapors and separately collecting resulting distillate, removing fixed gas from said distillate, combining fixed gas so removed with reflux condensate derived from said fractionating zone and passing the mixture through a reverting zone wherein it is subjected to reverting conditions of temperature and pressure and reaction between the gas and liquid occurs, passing the resulting products of reaction into a separating zone wherein vapors separate from liquid residue, fractionally condensing said vapors in a second fractionating zone to separate therefrom a heavy gas oil condensate, separately condensing the resulting fractionated vapors, passing said heavy gas oil condensate through a second cracking zone wherein it is raised to a cracking temperature and subjected to conversion, introducing the resulting cracked products into a second evaporating zone wherein vapors separate from liquid residue,
- 70 75 75

withdrawing said liquid residue from the process and introducing said vapors into said fractionating zone first-mentioned.

14. A process in accordance with claim 13 wherein an intermediate condensate is likewise separated in said second fractionating zone and intermediate condensate so obtained is introduced into said cracking zone first-mentioned for further conversion.

15. A process in accordance with claim 13 wherein the temperature in said reverting zone is from 800° to 950° F. and the pressure therein is in the neighborhood of 1000 pounds per square inch.

16. The process of treating hydrocarbon oil which comprises passing said oil through a cracking zone and subjecting it to cracking conditions therein, separating the resulting cracked products into vapors and unvaporized residue, fractionating said vapors to separate a higher-boiling fraction as reflux condensate, a lower-boiling fraction as a desired distillate product and fixed gas, combining said fixed gas with said reflux condensate fraction, passing said mixture through a reverting zone wherein it is subjected to reverting conditions of temperature and pressure, and reaction between the liquid and gas occurs, separating the resulting reverted products into vapors and residue, fractionally condensing said vapors to form a high-boiling condensate fraction and a plurality of lower-boiling condensate fractions, returning one of said lower-boiling fractions to said first-mentioned cracking zone and withdrawing the remainder of said lower-boiling fractions as final products of the process.

17. The process of treating hydrocarbon oil which comprises passing said oil through a cracking zone and subjecting it to cracking conditions therein, separating the resulting cracked products into vapors and residue, fractionating said vapors to separately condense a higher-boiling fraction as reflux condensate, a lower-boiling distillate fraction and fixed gas, treating said fixed gas to remove hydrogen and methane therefrom, combining the hydrogen and methane-free gas with reflux condensate, passing the mixture through a reverting zone wherein it is subjected to reverting conditions of temperature and pressure, and reaction between the gas and liquid occurs, separating the resulting reverted products into vapors and residue, fractionating said last-

named vapors to separately condense a higher-boiling condensate and a plurality of lower-boiling condensate fractions, passing one of said lower-boiling condensates to said cracking zone for further treatment therein and withdrawing the remainder of said lower-boiling fractions as final products of the process.

18. The process of treating hydrocarbon oil which comprises passing said oil through a cracking zone and subjecting it to cracking conditions 10 therein, separating the resulting cracked products into vapors and residue, fractionating said vapors to separately condense a higher-boiling fraction as reflux condensate, a lower-boiling distillate fraction and fixed gas, combining fixed gas 15 so separated with said reflux condensate, passing said mixture through a reverting zone wherein it is subjected to reverting conditions of temperature and pressure, and reaction between the gases and liquid occurs, separating said resulting products into vapors and residue, fractionating said last-named vapors to separately condense a high-boiling condensate fraction, an intermediate condensate fraction and a final distillate fraction and passing said intermediate condensate fraction to said cracking zone for further treatment therein.

19. A method of treating hydrocarbon oil which comprises passing said oil through a conversion zone and subjecting it to cracking conditions 30 therein, separating the resulting cracked products into vapors and residue, fractionating the vapors to separately condense a higher-boiling fraction as reflux condensate, a lower-boiling distillate product and fixed gas, treating said gas 35 to separate hydrogen and methane therefrom, thereafter combining the hydrogen and methane-free gas with said reflux condensate, passing said mixture through a reaction zone and subjecting it to conditions of temperature and pressure 40 therein adequate to effect a recombination of the products passing therethrough, thereafter separating the reaction products into vapors and residue, fractionating the last-named vapors to form a higher-boiling condensate fraction, an intermediate fraction and a light distillate fraction, 45 returning said intermediate condensate fraction to said first-mentioned cracking zone and withdrawing said light distillate fraction as a final product of the process.

HAROLD V. ATWELL.
